UNITED STATES PATENT OFFICE.

FREDERICK C. STIMMEL, OF CHATTANOOGA, TENNESSEE, ASSIGNOR TO THE CASEY-HEDGES CO., OF CHATTANOOGA, TENNESSEE, A CORPORATION OF OHIO.

WATER-TUBE BOILER.

Application filed September 14, 1923. Serial No. 662,629.

This invention relates to water-tube boilers of the multipass type and in which a preheating or economizer section is arranged in rear of the main boiler section.

5 One object of the present invention is to provide an improved and simplified arrangement of baffles between the lower and upper banks or sets of tubes of the main boiler section, said baffles extending through 10 the central portion of the triangular space bounded by the lower, upper and rear banks or sets of tubes of the main boiler section. This arrangement of said baffles affords a 15 very valuable space for the location of a superheater above the lower set of tubes and below the upper sections of said baffles.

Another object of this invention is to 20 simplify the supporting means for the baffles just mentioned, an additional series of water-tubes being provided for this purpose, 25 said tubes extending through the central portion of the triangular space between the three banks of main boiler tubes and communicating at their lower ends with the mud drum of said main boiler section and at 30 their upper ends with the front upper drum of the same section. The use of these baffle-supporting tubes eliminates a considerable amount of complicated baffling heretofore incorporated in boilers of this type.

A further object of the invention is to provide for greater storage space for steam in the top drum of the preheating or economizer section of the boiler. This is accomplished by raising said section so that 35 its top drum is on a higher level than the top rear drum of the main boiler section, the water level being thus lowered in said top drum of the economizer section.

40 The invention will be first hereinafter described in connection with the accompanying drawing, which constitutes a part of this specification, and then more specifically defined in the claim at the end of the 45 description.

The drawing is a vertical section of a boiler constructed substantially in accordance with this invention, the section being taken transversely of the drums and in line 50 with the water-tubes running between them.

The setting of the boiler includes the front wall 1, rear wall 2, and roof 3, and in said setting there is arranged the firebox 4 bounded at the rear by the bridge wall 5. The main boiler section includes a

lower or mud drum 6 preferably seated on the bridge wall along the rear edge thereof, a front water drum 7 preferably mounted against the upper portion of the front wall 1 of the setting, and a rear steam and water drum 8 arranged under the roof 3 substantially in vertical alinement with the mud drum 6 and on a higher level than the drum 7. The lower bank or set of tubes 9 of the main boiler section extends from the mud 60 drum 6 to the front water drum 7 and is upwardly and forwardly inclined over the firebox 4. The upper bank or set of water-tubes 10 of the main boiler section extends under the roof 3 in an upwardly and rearwardly inclined position from the drum 7 to the drum 8, while the rear bank or set of tubes 11 of said main boiler section extends substantially vertically between said drum 8 and the mud drum 6. 70

75 It will be seen that this arrangement of the banks of tubes, 9, 10 and 11 of the main boiler section leaves a triangular space 12 between them and in the center of said main boiler section. Through the central portion of this triangular space a row of additional water-tubes 13 is arranged, said tubes communicating at their lower ends with the top of the mud drum 6 and at their upper ends with the rear wall of the front drum 7. Said tubes 13 are bent substantially 80 midway of their length so as to define a triangular portion of the space 12 below them and above the lower bank of tubes 9. The portions of the tubes 13 below the bends 85 therein extend upwardly from the mud drum 6 and are inclined slightly forwardly, and the portions of said tubes above their bends extend forwardly therefrom and are inclined slightly upwardly. This arrangement of the tubes 13 insures free circulation 90 of water therethrough and also provides convenient and simplified means for supporting a baffle wall 14 which extends from a point above the mud drum along the 95 portions of the tubes 13 below their bends, over said bends and for a considerable distance along the upper portions of the tubes above their bends. Because of the inclined 100 position of the tubes 13, said baffle wall 14 will maintain its position against them by gravity and no additional fastening means for said wall is required. It will be observed that said wall 14 partially incloses 105 the lower portion of the triangular space 12 110

in the center of the main boiler section, and that a superheater is arranged in said inclosed space just above the lower inclined tubes 9 and over the fire-box 4, the bent tubes 15 of said superheater extending substantially parallel to said tubes 9, while the headers or drums 16 of the superheater are protected from the direct action of the fire by a baffle 17 extending along the top of the bank of tubes 9 from the top of the mud drum to a point below the lower one of said headers 16. A baffle section 25 extends from the upper one of the headers 16 of the superheater to the tubes 13 adjacent the lower edge of the baffle 14 which is preferably arranged slightly above the level of said upper header 16. Another baffle section 26 is fitted between the headers of said superheater. The heated gases or products of combustion rising from the fire-box 4 are thus confined to the portion of the triangular space 12 below and in front of the baffle sections 14, 25, 26 and 17 in which the superheater is arranged.

25 The preheating or economizer section of the boiler comprises a mud drum 18, a steam and water drum 19 arranged substantially in vertical alinement therewith, and a bank or set of vertical water-tubes 20 extending between and communicating with said drums in rear of the bank of tubes 11 of the main boiler section. Said economizer section is raised slightly above the level of the main boiler section so that the water line 21 in the drum 19, which is on the same level as the water line in the drum 8, is located below the center of said drum 19, thus providing additional storage space for steam in said latter drum.

40 A row of water-tubes 22 extends from the top of the mud drum 18 of the economizer section to the lower portion of the top drum 8 of the main boiler section. The feed water for the boiler enters the drum 19 via pipe 35 and passes down through the tubes 20 to the mud drum 18 of the preheating section. From said drum 18 the water passes upward through the tubes 22 into the top drum 8 of the main boiler section, and from said drum 8 the water circulates through the several banks of tubes and drums of said main boiler section in the usual manner.

55 The gases or products of combustion passing upward from the fire-box 4 first encompass and circulate through the lower bank of water-tubes 9 of the main boiler section and immediately afterward act upon the bent tubes 15 of the superheater. Said gases then act upon the baffle-supporting water-tubes 13 thus promoting the circulation of the water and increasing the efficiency of the present boiler as compared with prior constructions in which the baffles at this point are not supported on additional water-tubes. From the space inclosed by the baffle 14 the products

of combustion circulate through the boiler as indicated by the arrows on the drawing.

Near the forward upper end of the baffle 14 there is an upwardly extending ridge or wall 23 which preferably forms a part of 70 said baffle and which directs the products of combustion upwardly so that they will encompass the upper bank of tubes 10 before passing rearwardly to the vertical bank of tubes 11. A baffle 24 is suitably supported along the rear row of the tubes 11 and extends from the bottom of the drum 8 to a point spaced above the top of the mud drum 6. This baffle 24 directs the products of combustion in a downward course around the tubes 11 and in rear of the baffle wall 14. A cross baffle 27 extends from the lower edge of the baffle 24 rearwardly to the tubes 22, so as to direct the products of combustion across the lower portions thereof and of the tubes 20 of the preheating section. 75

The chimney outlet 28 is preferably located in the upper portion of the rear wall 2 of the boiler setting, but may be placed in the roof at the rear of the drum 19 if desired. A baffle 30 is suitably supported against the rear row of the tubes 20 of the preheating section in front of the outlet 28, and a cross baffle 36 extends from the lower edge of said baffle 30 to the base of said chimney outlet. The arrangement of said latter baffles insures the circulation of the products of combustion among the tubes 20 and 22 throughout substantially their entire extent before escape can be found through 90 said outlet 28. 95

The superheater is supplied with steam from the top of the drum 19 via pipe 29. The drums 8 and 19 are connected above their water lines by tubes 31 which place the steam spaces in the upper portions of said drums in communication with each other. A baffle 32 is preferably arranged between the lower portions of the drums 8 and 19. The superheater may be supported in position by suitable frames in the side walls of the setting as indicated in dotted lines at 105 110 115 37, and said frames may rest upon standards also embodied in the side walls of the setting as shown in dotted lines at 38.

I claim:

A boiler of the character described having a lower drum, two upper drums, and three sets of water-tubes extending between said drums and arranged in triangular formation, 120 additional water-tubes extending from the lower drum to the front one of the upper drums through the central portion of the triangular space formed between said three sets of tubes, said additional water-tubes being bent intermediate of their ends and having upwardly and forwardly inclined portions below their bends, a baffle wall extending from the lower drum to a point beyond the bends in said tubes and having its upper 125 130

portion supported on said additional water-
tubes, an upwardly extending ridge on said
baffle wall near its front edge, and a super-
heater arranged above the lower set of water-
tubes and below said upper portion of the
baffle wall, said superheater having headers
at the rear end thereof, the lower portion of

10
said baffle wall extending from the lower
drum to a point below said headers for the
purpose specified.

In testimony whereof I have signed my
name to this specification.

FREDERICK C. STIMMEL.
